NOVELTY

Ralph L. Ralston, Jackson, Mich.

Application February 24, 1940, Serial No. 320,580

4 Claims. (Cl. 273—97)

The present invention relates to a toy and more particularly to a toy adapted for sale at carnivals, fairs, circuses, and the like.

The toy of the present invention is of the class having a body adapted to be thrown in the air and caught on a handle. One example of such a construction is disclosed in Patent No. 1,527,532 to Alcaraz. The present invention consists of an improvement over prior art construction in that the thrown body is in the form of a doll and is provided with parachuting means to control the falling movement of the body.

An object of the present invention is to provide a toy of the character described, having a body provided with parachute means to control its falling.

Another object of the invention is to provide a toy of the character described, having parachute means in the form of articles of clothing to control its falling.

A still further object of the invention is to provide a toy of the character described, having a body having one end of a string attached thereto and having the other end of the string slidably attached to the handle on which the body is to be caught whereby the string may be slid longitudinally on the handle to hold the body on the handle.

These and other objects will be apparent from the following specification when taken with the accompanying drawings, in which:

Fig. 1 is an elevation disclosing the body of the present invention mounted on the handle,

Fig. 2 is an elevation showing the manner in which one form of the invention is operated,

Fig. 3 is an elevation showing an alternative position for the string connected to the body,

Fig. 4 is an elevation showing another form of the invention,

Fig. 5 is a partial cross-sectional view of a portion of the form of the invention disclosed in Fig. 4,

Fig. 6 is an elevational view of the handle employed with the body of Fig. 4, and

Fig. 7 is an elevational view disclosing the manner of operating a further form of the invention.

Referring particularly to Fig. 1 of the drawings, the reference character 1 indicates a cane, preferably of the length of the usual walking cane. The cane 1 is provided with a threaded projection 2 for threaded engagement with a tapped bore 4 in a handle 5. Preferably at the point of connection between the cane 1 and the handle 5, the respective parts are of the same diameter. The upper end of the handle 5 is tapered to provide a pin 6. The top of the pin 6 is provided with a protuberance 7 for contacting with some noise making construction 8, details of which do not form a part of the present invention.

The noise-making mechanism 8 is within a body 9, preferably in the form of a doll. The body 9 in its preferred form is composed of some light moldable material such as Celluloid. At its foot portion, the body 9 is provided with an interior conical recess 10 for receiving the pin 6.

The body 9 is provided with a broad-brimmed hat 15 and a skirt 16, both of which act as parachutes to control the falling movement of the body 9. For providing a point of attachment for the string 17 and also for reinforcing the mounting of the noise-making mechanism 8, the body 9 has formed therein during manufacture a central wire 18 terminating at one end at the noise-making mechanism 8 and at the other end in an eye 19 at the head portion. The string 17 is connected to the eye 19 by a suitable hook 20. The opposite end of the string 17 is tied around the handle 5. As shown in Fig. 1 the end of the string 17 about the handle 5 is disposed in a groove at 21. However, as disclosed in Fig. 2, the groove may be dispensed with and the string may be slidably attached to the handle 5.

In Fig. 2 the invention is disclosed in full lines with the body 9 separated from the handle 5 and in dotted position in successive positions as it is operated in use. As the invention may be used with and without the cane 1, it is shown in Fig. 2 without the cane 1 attached.

In using the invention the hand 22 holding the handle 5 is swung to throw the body 9 up in the air, the object being to insert the pin 6 in the conical recess 10 in the foot portion of the body 9 as it is falling to catch and support it. In performing this operation the body 9 may start from the full line position shown in Fig. 2 or it may start from on the pin 6. As shown in the vertical view of the body 9, in dotted outline, as the body 9 falls, the skirt 16 flares outward to provide with the hat 15 a parachuting effect to control the falling of the body 9. It should be understood that the body 9 should be weighted so that it falls feet first. It is preferred that the construction of the body 9 be hollow and particularly light weight so as to give a maximum effect to the parachuting action of the hat 15 and the skirt 16.

Should it be desired to use the handle 5 and cane 1 as a walking cane combination or for some other reason to secure the body 9 to the handle 5, the hook 20 is unhooked from the eye 19 and the string 17 withdrawn from the opening 23 in the hat through which it passes. The hook 20 is then re-attached to the eye 19 and the hat 15 forced over the string 17 onto the head of the body 9. The opposite end of the string 17 is then slid down the handle of the cane 1 until the string 17 is taut. The body 9 is thus maintained against displacement with respect to the handle 5. It will be understood of course

that in holding the body 9 on the handle 5 in fixed manner, that the connection between the lower end of the string and the handle 5 must be purely a sliding one as shown in Fig. 2 and not in association with a groove 21 as is shown in Fig. 1.

Another form of the invention is disclosed in Fig. 4 wherein the cane 1 has attached to it a handle 25 of a somewhat different configuration to the handle 5 disclosed in Figs. 1 and 2. The handle 25 is provided with a pin 26 similar to the pin 6 of Fig. 1 and is also provided with a protuberance 27 for engaging with and actuating a noise-making mechanism 28. The essential difference between the construction of Figs. 1 and 2 and that of Fig. 4 is that the body 29 is provided at the lower end therewith with a conical insert 30, preferably of some light-weight metallic alloy. The lower edge of the insert 30 is turned upwardly into a flange 31 which is crimped against the lower end of the body 29 to clamp it to the insert 30 as shown particularly in Fig. 5. In order to make the connection between the body 29 and the insert 30 more secure, the lower end of the body 29 is provided with a bead 32 about which the rim 31 is crimped.

Another difference between the construction disclosed in Figs. 1 and 2 and the construction of Fig. 4 resides in the shape of the pin 26 which in addition to being conical is also provided with a substantially cylindrically portion 33, shown particularly in Figs. 6 and 7. The portion 33 engages with a cylindrical portion 34 in the insert 30. The function of the cylindrical portions 33 and 34 is to provide a connection between the handle 25 and the body 29 which is not as likely to become separated as in the case of the structure disclosed in Figs. 1 and 2. The construction of Fig. 4 also provides a more rigid connection between the sound-making mechanism 28 and the body 29 in that the former is pinned directly to the insert 30 by a pin 35.

In Fig. 7 the invention is shown in another form wherein the string 17 is dispensed with. Fig. 7 also illustrates all forms of the invention in use with the body about to be caught on the handle.

The specific type of noise-maker employed in association with the present invention is not important as it may consist of a bell, a vibrating reed, a horn, or anything else desired. Furthermore, while the drawing has disclosed the body as consisting of a girl doll, it will be obvious that it may consist of a boy doll, an animal, a flower, or any other object desired, so long as it may have associated with it, a parachuting means. While from the standpoint of appearance combined with effective parachuting action both the skirt 16 and hat 15 or their equivalents are desirable, it is to be understood that within the scope of the invention that only a single parachuting means be employed if desired. It is contemplated that the invention be employed with or without the cane 1 and accordingly it is to be understood that the term handle as employed in the claims is not to be limited to the specific handle disclosed in the drawings, but may mean any handle including the type of handle disclosed in the drawings, having a cane connected to it.

The noise-making mechanisms 8 and 28 which may be of any well known and suitable type is so

located that the act of catching the doll upon the handle will make a noise. Also, when the cane is being used as such, any downward pressure, as when one strolls along, will result in a noise each time the cane strikes the ground.

Having thus described my invention, what I desire to secure by Letters Patent and claim is:

1. A toy of the character described having a body adapted to be thrown into the air and caught on a handle, comprising a handle having a pin, a body having an opening adapted to receive said pin, parachute means on the body to control the falling movement of said body, and a string connected at one end to said body on the opposite side thereof from said opening and at the other end to said handle, the connection between said string and said handle being slidable whereby said string may be slid along said handle away from said pin to tighten said string to hold said body on said pin.
2. A toy of the character described having a body adapted to be thrown into the air and caught on a handle, comprising a handle having a pin, a body in the form of a doll having an opening at the foot portion thereof adapted to receive said pin, said body having a hat to act as a parachute to control the falling movement of said body, and a string, one end passing through an opening in said hat and detachably connected to the head portion of said body, the other end of said string being slidably connected to said handle whereby said portion of said string connected to said handle may be slid along said handle away from said pin to hold said body on said pin and said string may be removed at the other end from said body to permit running the string beneath the hat to connect it to the head portion of said body so that when said string is drawn downwardly with respect to said body to hold said body on said pin, the brim of the hat will not be crushed.

3. A toy of the character described having a body adapted to be thrown into the air and caught on a handle, comprising a handle having a pin, a body having an opening adapted to receive said pin, and a string connected at one end to said body on the opposite side thereof from said opening and at the other end to said handle, the connection between said string and said handle being slidable whereby said string may be slid along said handle away from said pin to tighten said string to hold said body on said pin.

4. A toy of the character described comprising a body member and a head member, said head member being in the form of a doll, one of said members having a pin and the other of said members having a socket, said pin being disposed in said socket when said head member is on said body member, and a noise maker carried by one of said members, said head member being arranged to be thrown into the air by said body member and caught by said body member, said noise maker being arranged to be actuated by said head member as it is caught on said body member to produce a noise, said doll being provided with an article of clothing forming a parachute to control the descent of the doll to make the catching of the same by the body member easier than it would be if no parachute were provided.

RALPH L. RALSTON.
